AUTOMATIC PHONOGRAPH

James L. Donaldson Morrison,
Benton Harbor, Mich.

Application October 27, 1941, Serial No. 416,747

30 Claims. (Cl. 274—10)

1

This invention relates to automatic phonographs, and more particularly to automatic record changers for phonographs.

Phonograph record changer mechanisms heretofore provided have not been entirely satisfactory because of their complexity; their relative high cost; their susceptibility to breakage or misadjustment if the operation of the tone arm is interfered with while the mechanism is set for the "automatic" changing of records; and also subject to misadjustment or breakage by improper manipulation.

Accordingly it is one of the objects of the present invention to provide a new and improved type of phonograph record changer which is of improved quality while at the same time more compact and inexpensive, and not subject to misadjustment or breakage by manual interference or manipulation of the tone arm, or by intentional or unintentional misuse of the manual controls of the record changer.

A further object of the invention is to provide a new and improved automatic record changer for phonographs in which the operation of the parts in proper sequence and properly coordinated is assured as against every manual interference with the movement of any part subject to such interference.

A further object of the invention is to provide an automatic record changer so constructed that the parts thereof may be produced by the most inexpensive manufacturing processes and yet free from warping, distortion, or wear that would interfere with the proper operation of the mechanism.

A most important object of applicant's invention is to provide a simple mechanism for operating the tone arm during the changing of the records, and which mechanism permits the tone arm to be moved manually or by an external force, if greater than the normal operating forces, without effecting the adjustment of the record changer mechanism.

Applicant's invention more specifically contemplates the provision of a cam for operating the tone arm which will permit manipulation of the tone arm independently of the cam, and which cam will again pick up its follower and bring the tone arm back to its proper location to begin the next cycle of operations.

A further object of the invention is to provide a cam that is capable of exercising complete control over the horizontal and vertical movements of the tone arm without additional mechanism.

2

Still another object of applicant's invention is to provide a simplified and improved record sensing mechanism for automatically changing the throw of the tone arm in accordance with the size of the record to be played.

It is also an object of the present invention to provide in an automatic record changer an improved releasable driving connection operating instantaneously upon mechanical or manual interference with the operation of the changer and operating automatically upon removal of that interference, to discontinue the operation of the changer upon such interference and return all of the parts thereof automatically to proper coordinated working relation after removal of such interference.

It is also an essential object of this invention to provide an automatic record changer, in which the maximum number of mechanisms composing the record changer, are stationary during the playing of each record, thereby reducing to a minimum the wear upon the several mechanisms, and also improving the quality of the sound reproduced by insuring that interference noises cannot be generated by mechanisms of the record changer operating during the playing of the records.

Applicant's invention further contemplates the provision of a new and improved control by which a single manually operable member is adapted to exercise complete control over the phonograph and the record changer, and enable an operator by means of such single member to turn the phonograph on or off; to set the phonograph for automatic or manual changing of the record; and to "reject" any record at any time.

Other and further objects and advantages of the invention will be apparent from the following description when taken in connection with the accompanying drawings, wherein—

Figure 1 is a top perspective view of a phonograph record changer embodying the present invention;

Figure 2 is an enlarged view of the left record supporting post, with the corresponding changer blade and supporting blade, a stack of 12 inch records represented as resting on the supporting blade.

Figure 3 is a view similar to Figure 2 showing the parts in a different position of operation;

Figure 4 is a fragmentary horizontal view partly in section taken along the line 4—4 of Figure 2, and diagrammatically illustrating an operation of the record sensing member;

Figure 5 is a fragmentary view in elevation

of the right record supporting post and illustrating the connection between the pair of changer blades.

Figure 6 is a view taken on line 6-6 of Figure 17 the view being turned 90° counterclockwise, the turntable being shown fragmentarily and partly in section.

Figure 7 is an enlarged fragmentary view in vertical section taken substantially along the line 7-7 of Figure 6;

Figure 8 is a reduced view taken on line 8-8 fo Figure 7 and turned clockwise approximately 180° with respect to Figure 7, parts being shown fragmentarily.

Figure 9 is a view taken on line 9-9 of Figure 6, the upper portion being shown in section.

Figure 10 is a vertical elevation of a portion of the mechanism shown in Figure 9 illustrating the position of the parts, portions being shown fragmentarily and in section.

Figure 11 is a vertical elevational of a portion of the mechanism shown in Figure 9 illustrating positions of the parts, portions being shown fragmentarily and in section.

Figure 12 is a vertical elevation of a portion of the mechanism shown in Figure 9 illustrating the position of parts, portions being shown fragmentarily.

Figure 13 is a view along line 13-13 of Figure 9 and partially in section.

Figure 14 is a view taken along line 13-13 and turned about 90°.

Figure 15 is a view in perspective and partly in section of an element of the mechanism;

Figure 16 is a view in perspective of a part of the mechanism shown in Figure 14;

Figure 17 is a view along line 17-17 of Figure 6 and partially in section.

Figure 18 is a fragmentary view in a horizontal section taken along the line 18-18 of Figure 17;

Figure 19 is a view similar to Figure 18 but showing the parts in different positions of operation;

Figure 20 is a diagrammatic view of mechanism controlling the operation of the record changer;

Figure 21 is a diagrammatic view of a portion of the mechanism shown in Figure 20, showing the parts in a different position of operation;

Figure 22 is a fragmentary bottom perspective view of part of the manually presettable control device;

Figure 23 is a view in perspective of the manually presettable control device;

Figure 24 is a view in perspective of the support casting for the manually presettable control device;

Figure 25 is a top plan view of a portion of the motor board and showing the knob and parts of the manually presettable device below the motor board.

Figure 26 is a view in perspective and partly in section of certain parts of the mechanism for operating the tone arm and automatically initiating operation of the record changer;

Figures 27, 28 and 29 are diagrammatic views illustrating the operation of the tone arm and of the record sensing device;

Figure 30 is a view taken along the line 30-30 of Figure 13 and turned about 90° counterclockwise.

Figure 31 is a view in horizontal section taken substantially along the line 31-31 of Figure 30, and showing the tone arm operating cam in plan; and

Figure 32 is a fragmentary view in perspective of a portion of the cam edge.

Referring to the drawings in detail, the supporting plate or motor board 2 is formed in any desired manner for mounting in a cabinet or other housing for a phonograph.

The usual turn-table 4 with an annular rim 6 is secured to a cylindrical block 8 (Figure 9) having one or more diametric slots 10 receiving line 5 the key or pin 12 projecting from the combined spindle and record guiding post 14. The turn-table 4 is driven by any suitable driving mechanism which preferably comprises an electric motor 16 (Figure 7) carried by a mounting plate 18 secured to the motor board 2 as by bolts 20 and by sound deadening washers or blocks 22. A sleeve 24 on the upper end of the motor shaft drivingly engages the periphery of a friction wheel 26, which in turn engages the rim 6 of the turn-table, thereby frictionally driving the turn-table. The friction wheel 26 is preferably journaled on a pin or stud 28 supported in any appropriate manner on a plate 30, in turn affixed to the plate 18 as by a stud or bolt 32 received in line 15 a slot 34 in the plate 30. A bolt or screw 38 carried by the plate 18 has its head received in opening 40 of the plate 30 to act as a guide and limit stop for the plate 30. A spring 42 fastened at one end of the plate 30 and at the other end line 20 to the plate 18 maintains the friction wheel 26 constantly in engagement with the rim 6 of the turn-table.

The stack of records to be played may be supported at diametrically opposite edge portions by line 25 supporting blades 44 and 46 (Figures 1 to 3), with which changer blades 48 and 50 cooperate. These blades may be of any suitable conventional construction and are arranged in pairs with each changer blade being hinged or pivoted as by pin 52 (Figure 5) to the supporting and releasing plate. The pair of blades 44 and 48 are mounted upon a vertical post or spindle 54 and the pair of blades 46 and 50 are mounted on a similar vertical spindle 56, each of the spindles being provided with a cap 58. The blades 44 and 46 are formed with elongated hub portions 60 through which the spindles 54 and 56 extend, and are releasably keyed to these spindles as by pins 62 (Figures 2, 3 and 9) fastened to the spindles and received in key slots 64 in the bottom edges of the hub portions 60. Thus it will be clear that each pair of record supporting and changing blades will be oscillated upon oscillation of its associated spindle, while at the same time each may be raised, thereby releasing the pin 62 from its slot 64, and each pair of blades swung out of the way to permit records to be placed manually on the turn-table 4.

Simultaneous movement of each changer blade 60 with its associated record supporting blade is assured by means of a pair of interengaging lugs 66 and 68 (Figure 5).

The tone arm 70 may be of any suitable conventional structure providing a recording head or pick-up 72 (Figure 17) including a record stylus 74, the pick-up being connected to the usual electric reproducer or amplifier (not shown) by means of cable 76 housed within the shell of the tone arm. This tone arm 70 may be mounted in line 65 a known manner for raising and lowering vertically from and onto the record to be played and for horizontal swinging or oscillating movement across records on the turn-table from and back to the usual tone arm rest 78 (Figure 1).

76 This mounting means may, for example, com-

prise a plate 80 (Figure 17) having side ears 82, to which is journaled a pivot pin 84 secured to the shell of the tone arm to form a horizontal pivot about which the arm may be raised and lowered. The plate 80 is secured to a vertical sleeve 86 swinging the tone arm about a vertical axis across the records. The sleeve 80 is journaled in a post 88 mounted in the conventional manner on the motor board 2 and secured against rotation. The tone arm is provided internally with a headed pin 90 pressed downwardly by a spring 92 into normal engagement with a plunger 94 received in the sleeve 86. The plunger 94 is raised by a plunger 96, also mounted in the sleeve 86 but at the lower end thereof, through the mediation of a spring 98 interposed between the two plungers.

The driving mechanism for the record changer is embodied in a single driving element comprising a spiral or wormlike member 100 (Figure 9) having two spirals or threads oppositely directed. The spiral member 100 is mounted on or pinned to the portion of the post or spindle 14 projecting beneath the motor board 2. The spiral member is journaled at opposite ends in bushings or hollow bosses 102 and 104 formed in the supporting frame 106 pending from the motor board to which it is fastened by bolts 108. A follower 110, the construction of which is best shown in Figures 13 and 20, engages the spiral thread of the driving element 100. This follower comprises a block having a semi-circular recess or groove 112 defined by oppositely beveled faces 114 and 116 forming a threadlike surface for engagement with the threads or spiral of the member 100. The follower 110 is formed or provided with a pivot pin 118 for pivotally mounting the follower on a mounting link 120 (Figure 9). The pivot pin 118 is formed or mounted in a position offset from the center of gravity of the follower so that the portion 122 (Figures 10 to 13 and 20) on one side of the pivot axis being greater than the weight of the portion on the outer side of the pivot axis, the follower may be automatically tilted to engage the spiral threads of the spiral or wormlike member 100. It should be noted that the spiral member 100 has below the spiral threads a reduced or unthreaded cylindrical section 124 (Figures 10 to 12), and that the follower 110 is positioned along this section, and, as will later be described is held out of engagement with threads of the spiral member. It should also be noted that the oppositely directed threads merge into each other at the top of the spiral member 100, so that, when the follower is engaged with this member, the motion of the follower will be reversed automatically after having completed a movement the full length of the spiral member.

The link 120 is pivoted as by a pin 126 (Figures 9 and 23) to the depending arm 128 of a mounting bracket 130. The pivot pin 118 of the follower 110 is received in a bushing 132 (Figure 9) mounted in a boss 134 of the link 120. The fit of the pin in the bushing is sufficiently loose and the link 120 is sufficiently long to permit the follower to move along the spiral member 100 without binding.

A driving pin 136 carried at the inner free end of the link 120 is received in a longitudinal slot 138 at the inner free end of a lever 140 pivoted at its other end as by a pin 142 to an ear 144 formed on the mounting frame 106 for the spiral member 100. The lever 140 is provided at its pivoted end with a general rectangular block 146 (Figures 14 and 15) constituting part of a load 75 plate 188. The teeth of the rack 204 mesh with

releasing protective device or clutch 148 (Figures 9 and 13). A sleeve 150 cast with or secured to the block 146 projects laterally from the block and receives the pivot pin 142. The sleeve 150 is received in the pivot opening of a companion clutch plate 152 (Figures 9, 13, 14 and 16), which also forms a driving lever pivoted at its upper end as by a pin 154 (Figure 9) to a driving link 156.

The block or clutch plate 146 has grooves 158 and 160 on opposite sides of the sleeve 150, each groove being bounded by side surfaces 162 and 164 flaring outwardly from the sleeve to an edge of the block. The side surfaces 162 and 164 of each groove also flare outwardly from the base of the groove.

The clutch plate 152 is provided on either side of its pivot opening 166 (Figure 16) with projections or lugs 168 and 170 complementary in shape to the grooves 158 and 160 to interfit with said grooves. The bounding side surfaces 172 and 174 of each projection are beveled at an obtuse angle to the surface of the plate 152 to properly interfit and engage the side surfaces 162 and 164 of the corresponding groove 158 or 160.

A coil spring 176 (Figures 13 and 14) encircles the sleeve 150 and is interposed between the plate 152 and an adjusting nut 178 threaded on the sleeve. A clamping nut 180 secures the nut 178 in adjusted position. A washer 182 positioned by a cotter pin 184 limits the adjustment. It will be evident that, if the movement of the driving link 156 is resisted while the follower 110 is moved along the spiral member 100, the swinging of the clutch plate 152 will also be resisted, and that the side surfaces 162 or 164 of grooves 158 or 160 will act as camming surfaces against the side surfaces 174 or 172 and urge the clutch plate 152 in a direction axially of the sleeve 150 against the force of the spring 176, and release the clutch plate 152 from the block 146. It will also be clear that the spring 176 will snap the projections 168 and 170 into the grooves 158 and 160 as soon as the follower 110 in its opposite movement realigns the grooves with the projections.

The driving link 156 moves backwardly and forwardly as the follower 110 moves up and down along the spiral member 100 and serves to cause opposite oscillation of both pairs of record supporting and changing blades 44, 46, 48 and 50. For this purpose the driving link 156 is pivoted at its outer end as by a pin or rivet 186 (Figures 6, 9, and 13) to a plate or multi-arm lever 188 provided with a split hub portion 190 on the spindle 56 and clamped thereto as by a bolt 192 carried by one outstanding ear of the hub 190 and threaded into the other outstanding ear thereof. A diametrically opposite arm of the plate 188 is pivoted as by a pin 194 (Figures 6 and 13) to a connecting link 196 pivoted at its opposite end as by pin 198 to a crank 200 having a split hub portion received and clamped to the spindle 54. It will be clear that by virtue of these connections the record supporting and changer blades 44 and 48 are swung simultaneously with but in an opposite direction to the record supporting and changer blades 46 and 50.

The tone arm 70 is raised and lowered and automatically swung toward its post 78 by an operator or actuating mechanism 202 (Figures 6, 13, 17, 18 and 19). This operator or actuating mechanism comprises a rack 204 fixed as by screws 206 (Figures 6, 13 and 17) to a link 208 pivoted at its other end as by pin 210 to the third arm of the plate 188. The teeth of the rack 204 mesh with

the teeth of a pinion 212 secured, as best shown in Figure 30, to the upstanding hub portion 214 of a driving cam 216 which both raises and permits lowering of the tone arm and swings the tone arm from its support to the record and returns it to the support. The pinion 212 may be pressfitted on the hub portion 214 and secured by the peened-over upper end of this hub portion as shown in Figure 30. The cam 216 is journaled on a stationary stud shaft 218 and positioned between a boss 220 of a mounting bracket 222 (best shown in Figure 24) and a washer 224 (Figure 30) on a reduced threaded portion 226 of the stud shaft, the washer being held against an abutting shoulder on the shaft by a nut 228. The stud shaft is fastened to the motor board 2 by bolt 230. The bracket 222 is provided with a plate-like portion 232 (Figures 24 and 30), which is fastened to the motor board by means of a washer 234 and a nut 236, the nut being received on the threaded portion 238 of the tone arm mounting post 88, the portion 238 depending from the post 88 and passing through an opening in the motor board and a corresponding opening 240 (Figure 24) in the plate 232 of the bracket 222.

The cam 216 is in the form of a disc having on its upper flat surface a plurality of cam grooves 242, 244, 246, 248, 250, 252, 254 and 256. The grooves 242 to 256, inclusive, control the swinging movements of a pin 258 (Figures 17 to 19) and the raising and lowering movements of the plunger 96. The pin 258 constitutes a cam follower and is slidably mounted for vertical movement in a hollow boss 260 (Figures 17 and 26) of a segmental crank 262. The crank 262 is provided with a hub portion 264 mounted on the driving sleeve 86 (Figure 17) and fastened thereto as by a set screw 266. The cam pin 258 is provided with a conical tip 268 for engagement in the cam grooves 242 to 254 and is resiliently pressed into the grooves by a spring strip 270 (Figures 17 to 19 and 26). Fixed at one end as by a screw 272 to a boss 274 formed integral with the segmental crank 262, the spring 270 overlies the enlarged head of the cam pin 258, as shown in Figure 17.

The groove 242, which may be termed "the playing groove" for it is this groove in which the cam pin 258 rests during the playing of the records and from and to which the pin moves during the operation of the record changer, extends from the edge toward the center of the cam disc, and may therefore be termed a "radial groove" in contradistinction to the grooves 244 to 256 which extend arcuately of the disc. The groove 242 does not of course extend along any radius of the cam disc, but is of curvilinear configuration and is concentric to the axis of the driving sleeve 86 for the tone arm 70. The side surface 276 of this groove 242 is sharply inclined, while the opposite rounded side surface 278 is of gradual inclination to facilitate the movement of the cam pin into the grooves 244 to 248. The groove 244 may be referred to as the 10-inch groove for it determines the initial setting of the tone arm to play a 10-inch record, and the groove 246 may be referred to as the 12-inch groove for it determines the initial setting of the tone arm to play a 12-inch record. The grooves 248, 250, 252 and 254 may be referred to as directing grooves for they direct the cam pin into one or the other of the grooves 244 and 246. Each of the grooves 242 to 248 is generally V-shaped in cross-section, as illustrated in Figure 30, and the grooves 250 to 254 are similarly generally V-shaped in cross-section. The directing groove

248 may be further termed "an initial directing groove" for it serves to direct the cam pin into the groove 246, when the operation of the phonograph is initiated with the tone arm initially on the rest member 78. This directing groove 248 intersects the groove 246 at the point A (Figure 31), and at the point of intersection A the groove 248 is more shallow than the groove 246 so as to provide an outer side surface for the grooves 246 at this point, and thereby prevent movement of the pin into the groove 248 as the cam is rotated in a counterclockwise direction, as seen in Figure 31. The 10-inch and 12-inch grooves 244 and 246 are generally spiral in form, being of constantly increasing radius from the entering ends 280 and 282, to their terminating ends 284 and 286 to thereby cause the cam pin and tone arm to move outwardly with respect to the cam and the record as the cam is rotated in a clockwise direction and to move inwardly as the cam is rotated in a counterclockwise direction.

The directing cam grooves 250 and 252 intersect the 10-inch cam groove 244 at the points B and C. The groove 252 continues from the point B to the point C. At the point C the groove 252 is of greater depth than the portion of the groove 244 extending counterclockwise from the intersection so that, as the cam rotates in a clockwise direction, the pin will be directed from the groove 244 or 250 into the groove 252. At the point B the groove 244 is deeper than the groove 250 so that, as the cam rotates in a counterclockwise direction it will, in passing from the point C, be directed into the groove 244 rather than the groove 250. The directing groove 252 intersects the 12-inch groove 246 at the point D, at which point the groove 246 is deeper than the groove 252 so that, as the disc rotates in a counterclockwise direction, the pin will continue to move along the groove 246 and will not be directed into the groove 252. The directing groove 254 intersects the 12-inch groove 246 at the point E and the 10-inch groove 244 at the point F. At both of these points of intersection the groove 254 is more shallow than the grooves 244 and 246, so that the cam pin will not move into groove 254 from the 12-inch groove 246 upon a clockwise rotation of the cam, unless continued movement of the pin along this groove is restrained, nor will the pin move into the groove 254 from the 10-inch groove 244 as the cam rotates in a counterclockwise direction. All of the cam grooves 244 to 254 are sufficiently shallow to permit movement of the cam pin from one to another groove or across the flat surface of the cam in the event that the movement of the tone arm is in any way interfered with during the operation of the record changer, intentionally or inadvertently.

The cam groove 256 for controlling the plunger 96 is of constantly increasing depth from the upper flat dwell surface of the cam to the lower flat dwell surface 288 in which the plunger rests in its lowest position during the playing of the records. The inclined or active surface of the cam groove 256 is so disposed in angular relation to the grooves 242 to 250 as to insure raising of the tone arm actuating plunger 96 before an outward swinging movement of the tone arm is initiated, and to retain the record stylus elevated from the record until the tone arm has been initially positioned for the playing of the record. It should be noted that the spring 98 between the actuating plungers 94 and 96 for the tone arm permits relative movement between these

plungers in the event of interference with the raising or the lowering of the tone arm.

Phonograph records in common use today may be classified as of two types in respect to the form of the terminating groove, that is, the groove into which the stylus moves from the end of the recorded groove. Thus, in one type of record known as the eccentric groove type, the terminating groove is eccentric to the center of the record, and therefore causes the stylus to move away from the center of the record as the stylus traverses said terminating groove. In the other type of record known as the concentric type, the terminating groove is concentric to the center of the record at a fixed distance from the center for all records of this type.

According to the present invention, mechanism is provided for assuring initiation of the operation of the record changer regardless of the type of record; specifically, means is provided for initiating operation of the record changer when the stylus is moved away from the center by an eccentric terminating groove, and means is also provided for initiating operation of the record changer when the stylus is positioned at a predetermined distance from the center of the record as when brought to this position by a concentric terminating record groove.

The follower 110 is normally held during the playing of the records in an ineffective position in the space below the threads of the spiral driving member 100 by a latch comprising a rod 290 (Figures 6, 10, 11, 13, 18, 19 and 20) journaled in a boss 292 (Figures 9 and 13) provided therefor in a side flange of the mounting frame 106 for the spiral member 100. The rod 290 is also journaled in a depending lug or arm 294 of the bracket 222 (Figures 13 and 24). At its inner end the rod is bent downwardly to provide a latching finger 296 adapted when positioned, as shown in Figure 11, to engage an edge of the follower 110 and prevent tilting of the follower by its counterweighted portion 122 into engagement with the oppositely directed thread of the spiral member.

Release of the follower, thereby permitting it to tilt into engagement with the upwardly directed thread of the spiral member, is effected by rotating the latching rod 290 and hence the latching finger 296 in a counterclockwise direction, as seen in Figure 11, or in a clockwise direction, as seen in Figure 20. This latching rod 290 and latching finger 296 form a part of the means for initiating the operation of the record changer in response to the stylus traversal of an eccentric terminating record groove, and also part of the means for initiating operation of the record changer in response to the stylus traversal of a concentric terminating record groove.

Means for operating the rod 290 in response to the stylus traversal of an eccentric terminating record groove comprises a rod actuator 298 (Figures 13, 18, 19 and 20) in the form of a special crank secured to the outer end of the rod 290 as by the screw 300 (Figure 13), the crank having a laterally directed curved lug 302. The surface 304 of this lug is roughly concentric to the axis of the sleeve 86 (Figure 17) and the coincident axis of swing of the tone arm 70. The outer round end 306 of the lug 302 normally lies substantially on the prolongation of the axis of the rod 290 while the surface 304 curves away from such prolongation of the rod axis.

The segmental crank 262 (see Figures 18, 19 and 26) is formed with a boss 308 receiving a

pivot pin 310, by which a pawl 312 is mounted on the segmental crank 262. A very light spring 314 is secured at one end to the pawl and at the opposite end is fixed as by a pin 316 to the segmental crank. The spring 314 normally maintains the pawl 312 in the position shown in Figure 18, in which the point of the pawl tooth 318 lies on the line of centers through the pivot pin 310 and the spring securing pin 316. This pawl may be said to be normally maintained "on center." The rod actuator or crank 298 is normally retained in the position shown in Figure 18 by a light spring 320 secured at one end to the lug 302, and at the other end to the pin or lug 322 formed on the bracket 222. As the tone arm moves inwardly across a record, the pawl 312 is swung in a clockwise direction (Figure 18) with the segmental crank 262 until the pawl tooth 318 engages the rounded outer edge 306 of the lug 302. As the segmental crank continues to swing in this clockwise direction, the pawl is caused to rotate in a counterclockwise direction about its pivot pin 310 until the pawl tooth clears the edge 306, after which the pawl tooth moves inwardly along the curved surface 304.

Due to the stylus traversing the eccentric terminating record groove, the tone arm and the segmental crank 262 are caused to rotate slightly in a counterclockwise direction, and the curved surface 304, which is in engagement with the point of the pawl tooth 318, causes the pawl to swing in a clockwise direction relative to the segmental crank and past the "on center" position of the pawl. As the pawl passes the "on center" position, it causes the crank 298 to rotate in a clockwise direction, as seen in Figure 17, and the rod 290 and latch finger 296 to rotate in the direction of the arrows (Figures 13 and 11). This, of course, effects release of the follower 110 for the initiation of an operation of the record changer. The means for operating the latch rod to initiate an operation of the record changer in response to the stylus traversal of the concentric terminating record groove, comprises the rod actuator or crank 298 which, for that purpose, is provided with a lug 324 (Figures 17 to 20, inclusive) extending below the lug 302. The lug 324 is engaged and actuated by an adjustable stop comprising a set screw 326 threaded in ear 328 extending outwardly from the segmental crank 262, the set screw being held in adjusted position as by the clamping nut 330. The lug 324 is offset from the axis of the rod 290 so that, when engaged by the set screw 326, the crank 298 is rotated in a clockwise direction, as shown in Figure 17, to cause the rod 290 and the latching finger 296 to be rotated in the direction of the arrows in Figures 13 and 11, and thereby release the follower for the initiation of an operation of the record changer.

Manually operable means 332 (Figures 1, 17, 20 to 23, and 25) is provided for turning the record player on and off; for rendering the record changer ineffective, so that the records may be manually placed on the turn-table; for setting the record changer for automatic operation; and for initiating operation of the record changer at any desired instant to reject or terminate the playing of any undesired record. This means comprises an actuating rod 334 journaled in a boss 336 (Figures 17 and 23) of the bracket 130 that carries the pivot pin 126 for the link 120. This bracket is secured to the motor board 2 by a nut 338 (Figure 17) and a washer 340, the 75 nut being threaded on the reduced lower end of

the mounting post 342 for the record supporting and changing blades 44 and 50. The rod 334 projects through the motor board and is provided with an operating knob 344.

A coil spring 346 interposed between the boss 336 and the knob 344 urges the rod upwardly to a position limited by the engagement of a radial pin 348 with the bottom of the boss 336. The rod is adjustable to three positions accurately set by radial grooves 350, 352 and 354 (Figure 22) in the lower surface of the boss 336, and movement of the pin 348 beyond the grooves 350 and 354 is prevented by stop pins 356 and 358 depending from the boss 336. The rod 334 carries at its lower end a crank arm 360 having a switch actuating lug 362 at its outer end to engage the operator of a switch 364 mounted on a web of the bracket 130 (see Figure 23). The crank 360 is provided with an arm 366 having a slot 368 receiving the upturned end of a latch rod 370 (Figures 6, 9 to 13, 17, 20 and 21). The rod may be secured to the arm 366 as by a cotter pin or the like 372. The rod 370 extends from the arm 366 and is slidably mounted at its other end in a boss 374 (Figures 10 to 12) formed on a flange of the mounting frame 106 for the spiral member 100. As the knob 344 is turned to the position in which the pin 348 is received in the groove 354, the rod 370 is moved longitudinally from the position in Figures 9 to 11, inclusive, to the position in Figure 12, in which the free end of the rod extends over the edge of the follower 110 and restrains the follower in the horizontal, uniltted position and out of engagement with the threads of the spiral member 100. Thus, with the knob in this position, the record changer is rendered ineffective, so that the records may be placed by hand on the turn-table. As the knob 344 is rotated to the position in which the pin 348 is received in the groove 352, the rod 370 is withdrawn from the follower to the position as shown in Figures 10 and 11, thereby rendering the record changer effective for automatic operation.

The pin 348 serves not only to determine the various adjusted positions of the knob 344, but also serves to actuate the mechanism for initiating operation of the record changer at any desired instant to reject any record or terminate the playing of any record when desired. This mechanism comprises a rod 376 (Figures 13, 17 and 20) journaled at one end in a lug 378 formed as a part of the bracket 130 and in the lug 294 of the bracket 222. A crank 380 (Figures 17 and 20) is pinned to the end of the rod 376 adjacent the manual adjustor rod 334, the crank extending beneath the pin 348 for engagement thereby when the knob 344 and the rod 334 are depressed against the action of the spring 346. The rod 376 has at its opposite end an upturned end portion 382 for engaging the rod actuator or crank 298. The engaged surface 384 of the crank 298 is so shaped that upon depression of the pin 348 and the consequent turning of the rod 376 in the direction of the arrow in Figure 20, the crank 298 and the rod 290 will be rotated in a clockwise direction, as seen in Figure 17, or in the direction of the arrow in Figure 20. Such rotation of the rod 290 causes the latch finger 296 to be released from the follower 110, thereby initiating an operation of the record changer. When the manual adjustor rod 334 is in its upward position, as shown in Figure 17, the pin 348 is out of engagement with the crank 380. The crank is, however, provided with an upwardly extending nose or cam surface 386 at its

outer free end, which is normally positioned in the path of the pin 348 as the knob 344 is rotated to the manual position in which the latch rod 370 is moved to latch the follower 110. Thus, as the rod 370 is moved to latch the follower 110, the pin 348 engages the cam part 386 of the crank 380 to rotate the rod 376 in the direction to release the latch finger 296 from the follower. This insures that, when the knob 344 is turned from the manual to the automatic position and the latch rod 370 is thereby released from the follower 110, the latch finger 296 will not retain the follower in ineffective position, but an operation of the record changer placing a new record on the turn-table, will be initiated.

Automatically operable means is provided for automatically determining the position of the tone arm in accordance with the size of record to be played. This means comprises a record sensing device or feeler rod 388 (Figures 1 to 4, inclusive, 6, 9, 13 and 27 to 29, inclusive) journaled in the post or spindle 54 by being received in a longitudinal surface groove or slot 390 (Figure 9). The rod 388 extends below the spindle 54 and has adjustably secured to its lower end a crank 392. The rod is provided with an integral crank formed by a bend 394 in the rod, the bend 394 extending from the spindle through an arcuate slot 396 at the upper edge of a mounting post 398 which supports the pair of blades 44 and 48, and in which the spindle 54 is journaled. From the bend or crank portion 394 the rod extends upwardly alongside the inner edge of the record supporting blade 44 and terminates just above the plane of the upper surface of this blade so as to engage the periphery of the bottommost 12-inch record in the stack of records on the blade. It should be noted that this free end portion 400 of the rod extends above the blade 44 a distance which is somewhat less than the thickness of a record, so that the rod will not engage the periphery of the second record in the stack, and will freely move beneath the edge of a 12-inch second record, if the bottom record of the stack is the 10-inch size. The upwardly extending portion 402 of the rod acts as a guide for the periphery of the record as it drops toward the turn-table. This portion is made sufficiently long to insure that the record will drop without substantial tilting on the guide post 14, and is made sufficiently short as by bends 404 and 406, as not to appreciably retard the dropping of the record, which would in itself tend to cause tilting of the record

The spindle 54 is provided in the plane of the crank portion or bend 394 with a transverse slot 408 (Figures 4 and 9) for permitting the crank portion to swing about the axis of the rod 388 relative to the spindle 54, as the rod revolves about the axis of the spindle. The rod 388 controls the positioning of a stop rod 410 (Figures 2, 3, 6, 9, 13, 18, 19, and 27 to 29, inclusive). The rod 410 is pivotally secured to the crank 392 as by the upwardly bent portion 412 (Figure 9) of the rod which is received in a pivot opening in the crank, and the rod is secured against release from the crank by the upwardly bent end 414 of the rod. The rod is slidably guided adjacent its opposite end in the aperture provided in a depending lug 416 (Figures 6, 13, 17 to 19, inclusive, and Figure 24) formed integrally with the bracket 222. This end of the rod is adapted 70 to be positioned in the path of movement of an

arm or lug 418 formed integrally with the segmental crank 262.

A coil spring 420 (Figures 6, 13, and 27 to 29, inclusive), which is secured to the fastening pin 422 of collar 424 thus secured to the rod 410, and at the other end to the lug 416, urges the rod 410 in the direction of the arm or lug 418 of the segmental crank 262 when the bottom record of a stack of records supported upon the blades 44 is of 10-inch size. A 12-inch bottom record engaging the end 400 of the feeler rod 388, holds the rod 410 against action of the spring 420 in a position out of the path of the arm or lug 418.

As the blades 44, 46, 48 and 50 swing in the direction of the arrows (Figure 1) to release the bottommost record of the stack, the end 400 of the feeler rod engaged by a 12-inch record will thereby be held against movement, and the spring 420 will thereby be rendered ineffective to move the stop rod 410 into the path of the lug 418. Consequently the cam pin 258 traverses the 12-inch record groove to the end 286 thereof without interference. Although the spindle 54 in rotating to effect a swinging of the blades 44 and 48, causes a revolution of the feeler rod 388 about the axis of the spindle, this will not effect the advancement of the stop rod toward the lug 418, because the end 400 of the feeler rod being held against movement by a 12-inch record, is caused to rotate relatively on its own axis to axis 54 in a counterclockwise direction, as seen in Figure 4, or in a clockwise direction, as seen in Figure 13, thereby compensating for any advancing movement imparted to the rod 410 by the revolution of the feeler rod 388 about the axis of the spindle 54.

When the end 400 of the feeler rod 388 is not restrained against movement by a 12-inch record (the bottom record of the stack being of 10-inch size), the swinging of the blade 44 in the direction of the arrow in Figure 1 permits the end 400 of the feeler rod to move in a clockwise direction, as seen in Figure 4, to the full line position in that figure, and this movement of the feeler rod effects a clockwise movement of the crank 392, as seen in Figures 27 to 29, or a counterclockwise movement of this crank as seen in Figure 13. This movement of the feeler rod and the consequent advancement of the stop rod 410 to the position shown in Figures 18 and 29 are effected by the spring 420. The crank 392 is angularly adjusted or positioned on the feeler rod 388 so that the end of the stop rod 410 will engage the arm or lug 418 of the segmental crank 262 at the instant that the cam pin 258, in traversing the 12-inch record groove 246 of the cam 216, reaches the intersection E, and the rod 410 continues to advance, pushing upon the arm or lug 418 and forcing the cam pin 258 into the cam groove 254, which thereby directs the pin into the 10-inch groove 244. The cam continues to rotate until the cam pin 258 reaches the end 284 of the 10-inch cam groove 244. During this movement of the blades in the direction of the arrows in Figure 1, the follower 110 is moved upwardly of the driving spiral member 100 and the cam 216 is being rotated in a clockwise direction, as seen in Figures 6, 18, 19 and 27 to 29, inclusive, and in a counterclockwise direction, as seen in Figure 13. By the time that the follower has moved to the top of the spiral member, the record supporting blades 44 and 46, having released the bottommost record, the changer blades 48 and 50 have been inserted between the bottom record and the stack thereabove, and

the cam 216 has completed its movement. As the follower descends along the spiral member, the blades 44, 46, 48 and 50 are swung in an opposite direction from the position shown in Figure 3 to the position shown in Figure 4, and the cam 216 is rotating in a counterclockwise direction, as seen in Figures 6, 18, 19, 27 to 29, inclusive, or in a clockwise direction, as seen in Figure 13. During this movement of the cam, the cam pin 258 traverses the 10-inch groove 244 and the tone arm 70 is brought to the proper position to initiate the playing of a 10-inch record.

The operation of the machine is as follows: A preselected set of records is positioned on the record supporting blades 44 and 46 and the guide post 14, the records being arranged in series without regard to their size. The control knob 344 is swung to automatic position, and, as it is swung to this position, the wiper blade 362 of the crank 360 (Figures 17 and 25) engage the actuator of the switch 364 to close the circuit to the driving motor 16. If the first record to be played has not manually been placed on the turn-table, the control knob is then depressed, causing the pin 348 to engage and operate the crank 380 and thereby rotate the releasing rod 376 in the direction of the arrows in Figures 13, 17 and 20. The end 382 of the release rod 376 causes the latch rod 290 to move in the direction of the arrow in these same figures through the crank 298, thereby releasing the latch finger 296 from the follower. An operation of the record changer is thereby initiated automatically to place a record on the turn-table. The stylus and tone arm thereafter move across a record in playing the same, and if the record is of the type having an eccentric terminating groove, the segmental crank 262 (Figures 18 and 19) is caused to move in a counterclockwise direction, thereby dragging the tooth 318 of the pawl 312 across the surface 304 of the special crank 298 from the dotted line position A in Figure 19 to the dotted line position C through the "on center" full line position B. This movement of the pawl relative to the segmental crank causes the special crank 298 to be rotated in a clockwise direction, as seen in Figure 20, thereby rotating the latch rod 290 in the direction of the arrows in Figures 13, 18, 19 and 20. This effects a release of the latch finger 296 from the follower 110 and an operation of the record changer is automatically initiated. If the record is of the type having a concentric terminating groove, the tone arm is carried inward sufficiently far to cause the set screw 326 carried by the segmental crank 262 to engage the lug 324 of the special crank 298 and cause a similar operation of this crank to release the follower 110.

At the instant that the follower is thus released for an automatic operation, the cam pin 258 is positioned in the cam groove 242 (see Figure 31) somewhere between the entering end 280 of the 10-inch groove 244 and the cam groove 250. Hence, as the follower moves upwardly along the spiral member 100 and the cam 216 rotates in a clockwise direction, as seen in Figure 31, the pin rides over the surface 278 of the cam groove 242 and into the cam directing groove 250, thence along the cam groove 252 into the 12-inch cam groove 246 at the point D. If the bottommost record of the stack is of the larger size—namely, 12-inch—the pin continues to traverse the groove 246 to the end 286 thereof, as previously described. If the record is small—namely, 10-inch size—the follower rod 388 of the record sensing

device advances the stop rod 410, as previously described, and this rod 410 by engagement with the arm or lug 418 of the segmental crank 262 causes the pin to pass into the directing groove 254 at the point E, and thence to traverse this groove and the 10-inch groove 244 to the end 284. During this operation of the cam the record supporting and changing blades are swung in the direction of the arrows in Figure 1 to the position shown in Figure 3, thereby releasing the bottom-most record which drops upon the turn-table.

As the follower then moves downwardly along the spiral member 100, the cam 216 is rotated in a counterclockwise direction, as seen in Figure 31, and the record supporting and changing blades are moved opposite to the direction of the arrows in Figure 1 from the position of Figure 3 to the position of Figure 2. In the counterclockwise movement of the cam 216, the cam pin 258 traverses the 10-inch cam groove 244 from the end 284 past the intersections C and B to the entering end 280 of this cam groove. The ends 284 and 286 of the 10-inch and 12-inch cam grooves 244 and 246 are spaced radial distances from the center of the cam sufficiently to cause the tone arm to be positioned out of the path of the record falling onto the turn-table. The entering ends 280 and 282 of these grooves are, however, spaced nearer to the center of the cam axis, and these radial distances are such as properly to position the stylus 14 in respect to the starting record groove. As previously noted, the cam surface 256 is so related to the cam grooves 242 as to cause the tone arm to be raised from the record before the outward swinging movement of the arm is initiated, and to maintain the tone arm raised until it has been swung to proper position for the playing of the next record.

Whenever it may be desired to terminate the playing of any record, or "reject" the same, it is merely necessary to depress the control knob 344, and this depression of the control knob effects in the manner previously described the release of the latch finger 296 from the follower 110, and an operation of the record changer is thereby initiated to swing the tone arm from the record on the turn-table outwardly while the record supporting and changer blades release the bottom-most record of the stack, and the tone arm is then returned for the playing of the next record.

If it is desired to dispense with the automatic feeding of the records, and to manually position the desired records individually on the turn-table, it is merely necessary to swing the control knob to the manual position, and to lift each pair of record supporting and changing blades on their spindles 54 and 56 to swing them out of the way, so that a record may be placed manually on the turn-table. The movement of the control knob to manual position causes the latch rod 370 to be advanced from the position of Figure 10 or 11 to the position of Figure 12, so as to latch the follower 110 against automatic operation. The tone arm may then be positioned manually to initiate the playing of a record, and when the record has been played, the arm may be manually returned to its rest member 18.

The spring pressed cam pin 258 permits manipulation of the tone arm without interference, the cam pin simply moving up and down as it is caused to swing across the surface of the cam 216, and in the same manner any interference with the tone arm, while it is being moved by the cam 216, will not affect the operation of the cam since the cam pin will simply rise in its socket 260

(Figure 17) against the urging of the spring 270. When such interference of the tone arm has been terminated, the cam pin will automatically be returned to proper position upon the next operation of the cam.

Any interference with the changer blades, such as may be caused by a warped record or by grasping one of the blades during its operation, will not affect the adjustment of the record changer mechanism for the release mechanism or clutch 148 will immediately come into operation, freeing the driving lever 140 from the combined lever and clutch plate 152, so that the follower member 110 continues its movement along the spiral member 100. As soon as the clutch projections 168 and 170 again become aligned with the clutch grooves 158 and 160 by the movement of the follower in the opposite direction along the spiral member, the driving lever 140 and lever 152 will automatically be returned to their normal driving relation.

It frequently is desired to repeat the playing of a particular record. This can readily be accomplished by turning the control knob 344 to manual position, thereby preventing automatic operation of the record changer, by advancing the rod 370 to the position in Figure 12, and manually moving the tone arm to proper position for playing the record a second time. When the knob 344 following the second playing of the record is swung to automatic position to reset the changer for automatic operation, the latch rod 370 is released from the follower before the latch finger 296 is returned to latching position, for the pin 348, by engaging the cam lug 385 of the crank 380, retains the crank depressed for a slightly greater angular movement of the control knob than is required to release the latch rod 370. Thus the follower being released automatically by resetting the control knob for automatic operation, a next record from the stack is automatically fed to the turn-table. This release of the latch rod 370 prior to the movement of the latch finger 296 into latching position, insures the placing of a record on the turn-table whenever the tone arm is automatically positioned for the playing of a record. For example, if a stack of records is placed upon the supporting and changing blades, there being no record on the turn-table, the tone arm will not automatically be placed over the turn-table for the follower will either be latched by the finger 296 or by the latch rod 370. If the control knob is in off position, then it must be either turned to the manual or automatic position to start the record playing. If it is turned to the automatic position, it must be further depressed to release the latch finger 296 from the follower, thereby initiating the automatic operation in which the bottom record of the stack is placed on the turn-table. If the knob is moved to manual position, then the follower is latched by the rod 370 until the control arm is turned to the automatic position. The depression of the knob while in the manual position will not release the follower, but as soon as the knob is turned to the automatic position, the follower will be released, as previously described, and an automatic operation of the record changer effected thereby to place the record on the turn-table.

It will be obvious that changes may be made in the form, construction and arrangement of the parts without departing from the spirit of the invention or sacrificing any of its advantages,

and the right is hereby reserved to make all such changes as fairly fall within the scope of the following claims.

Having thus described my invention, what I claim as new and desire to secure by Letters Patents is:

1. In an automatic record changer, a driven, record turntable, a shiftable record changing member, a driving threaded spiral connected to and driven with the turntable, a follower for said spiral, said follower being connected to said record changing member to shift the same and mounted for movement relative to the spiral from an ineffective position out of engagement with the thread of the spiral to an effective position in engagement with the thread of the spiral, and means controlled by records for moving said follower from said ineffective position to said effective position.

2. In an automatic record changer, a driven, record turntable, a shiftable record changing member, a tone arm, a shaft connected to and driven with the turntable and having spiral threads, a follower connected to said record changing member and having a spiral thread for interfitting with the spiral threads on said shaft, said follower being connected to said record changing member to shift the same when the follower is moved along said shaft by interengagement of the follower thread with the spiral threads on said shaft, said spiral thread and follower having means for automatically engaging its thread with said spiral thread adapted to move the follower to an effective position, means for latching said automatic engaging means against actuation, and means responsive to movement of said tone arm to the end of a record being played for releasing said latching means.

3. In an automatic phonograph, a turn-table, a tone arm, a motor for driving said turn-table, means for supporting and successively releasing records to be played, said means including a record supporting member shiftable to release a selected record, a worm having a threaded portion and an unthreaded portion and driven by said motor, a follower connected for operation of said shiftable record supporting member and having a thread adapted to engage the worm thread to actuate said member when the worm threads are so engaged, said follower being moved automatically by the worm from the threaded portion of the worm to the unthreaded portion of the worm, means normally urging said follower onto the threaded portion of the worm, means for releasably retaining said follower on the unthreaded portion of the worm against the action of said urging means, and means responsive to movement of said tone arm to the end of record being played for operating said retaining means to release the follower for automatic movement by said urging means onto the threaded portion of the worm.

4. In an automatic record changer, a record changing member shiftable to and fro, a driving spiral having superposed coextensive right and left hand spiral threads, a follower having automatic means for causing said follower thread to interfit with the threads of the spiral and movable first in one direction and then in the other as the thread of the follower traverses first one thread of the spiral and then the other, said follower being connected to shift said record changing member to and fro as the follower moves first in one direction and then in the other along

the spiral, said follower having means for automatically moving it from a normal ineffective position in which the thread of the follower is out of engagement with the spiral to a position in which the thread of the follower engages the thread of the spiral, and releasable means for latching said follower in said ineffective position.

5. In an automatic phonograph, a record receiving turn-table mounted on a spindle, a stylus carrying tone arm shiftable mounted for movement across a record on the turn-table and for movement toward and from a record on the turn-table, a vertical driving spiral driven by said spindle, said spiral having superposed coextensive right and left hand threads, a follower having a thread automatic means for causing said follower thread to interengage first one thread and then the other of the spiral, whereby the follower traverses the spiral first in one direction and then in the opposite direction, means connecting said follower to said tone arm for moving said tone arm away from and across said turn-table in an outward direction as the follower moves in one direction along the spiral to permit placement of a record on the turn-table, said connecting means moving said tone arm inwardly with respect to the edge of the turn-table and then toward said turn-table as the follower moves in the opposite direction along said spiral to reposition the tone arm to initiate playing of a record placed on the turn-table, latch means for normally retaining said automatic means in ineffective position with follower at one end of said spiral out of engagement with the threads of the spiral, and means controlled by the tone arm for releasing said latch means thereby to cause said follower to engage with the threads of the spiral.

6. In an automatic record changer, means for supporting and successively releasing the bottom-most record of a stack, said means including a record supporting member shiftable to release the bottommost record, a tone arm, a tone arm operator constructed to shift the tone arm from one record after it is played to the next as the records are changed, a continuously operating driving spiral, a follower automatic means for connecting said follower to said driving spiral releasable latch means for normally retaining said automatic means against operation, means connected to said follower for synchronously operating said record supporting member and said tone arm operator and means operative by the tone arm when it reaches the end of a record groove, for releasing said latch means.

7. In an automatic record changer, record supporting and changing blades for supporting a stack of records and oscillatable to and fro to release the bottommost record, a turn-table positioned to receive the released record from the supporting and changing blades, means for turning said turn-table driving means automatic means for effecting operation of said driving means by said turning means, means connecting said driving means to said record supporting and changing blades for oscillating said blades to and fro, a tone arm mounted for raising and lowering movement to and from the turn-table and for movement across the turn-table, a cam oscillatable to and fro, means connecting said cam to said driving means for oscillation in synchronism with said supporting and changing blades, means operated by said cam for raising the tone arm from the record and swinging said tone arm outwardly above the turn-table as the cam and changer

blades swing in one direction, and swinging the tone arm inwardly above the turn-table and downwardly onto a record on the turn-table as the changer blades and cam swing in the opposite direction, means for normally maintaining automatic means ineffective, and means controlled by the records through the tone arm as it reaches the end of each record being played, for rendering said automatic means effective to effect operation of said driving means.

8. In an automatic phonograph, a stylus carrying tone arm for playing the records, means for automatically raising the tone arm from a record when the record has been played and for repositioning said tone arm to initiate playing of a record, said means comprising a pair of cam surfaces adapted to position the tone arm for the playing of a record of 10" or 12" size respectively, a follower connected to the tone arm and normally positioned to engage that one of said cam surfaces for positioning the tone arm for playing a 10" record, and record sensing means responsive to the dropping of a 12" record for positioning the follower to engage the other of said cam surfaces for positioning the tone arm accordingly.

9. In an automatic phonograph, a record receiving turn-table, opposite sets of record supporting and changing blades for receiving a stack of records to be played, said blades being oscillatable to and fro to release the records one by one, means for guiding the released records to the turn-table, a stylus carrying tone arm mounted for movement toward and from the turn-table and for movement across the turn-table, and means for synchronously operating said changing blades and said tone arm, said means including an actuating cam means providing a pair of cam surfaces for positioning the tone arm for playing a record of one size or another size respectively, cam follower means connected to the tone arm and normally positioned to engage that one of said surfaces for positioning said tone arm for playing the smaller size of records, a record sensing member connected to one set of said blades for movement therewith to gauge the periphery of a record to be released from said supporting and changing blades, and means operated by said record sensing member in response to its gauging of a larger size record for positioning the follower means to engage the other of said surfaces for positioning said tone arm accordingly.

10. In an automatic record changer, a driven, record turntable, a shiftable, record changing member, a shaft driven with the turntable and having a pair of opposite coextensive spiral threads, a follower having a thread formed to interfit with the spiral threads and to actuate the follower longitudinally of the driving shaft first in one direction and then in the other, means connecting said follower to said shiftable record changing member to operate said member as the follower moves longitudinally of the shaft, means for latching the follower against engagement with said spiral threads, means for releasing said latching means to permit engagement of said follower at one end of said shaft spirals and means at the other end of said spirals for directing said follower thread into the reverse spiral for the return movement.

11. In an automatic phonograph, a horizontal turn-table, a tone arm shiftably mounted for movement above said turn-table, a vertical shaft connected to the turn-table for continuous operation therewith and extending beneath said turn-table, said shaft having superposed

spiral threads on the portion below said turn-table, a follower having a portion for interfitting with the spiral thread to cause a cycle of movement of the follower longitudinally of the shaft, means connecting said follower to said tone arm for moving the tone arm from a record being played and repositioning it on a record to be played as the follower moves through its cycle of movement, latching means for normally retaining the follower disengaged from said spiral threads, means for automatically releasing said latching means upon the completion of the playing of the record, and means for automatically engaging said follower with said threads upon release of said latching means.

12. In an automatic phonograph, a turn-table, a tone arm operably associated with said turn-table, a driving shaft for said turn-table having a spiral thread, a follower having a portion for interfitting with the spiral thread to move said follower longitudinally of the shaft when engaged with said thread, means connecting said follower to said tone arm for moving the tone arm from a record being played and repositioning it on a record to be played, said connecting means including interengaged members releasable upon manual movement of the tone arm, means for latching the follower against engagement with said spiral thread, means controlled by the tone arm for automatically releasing said latching means, and manually operable means for preventing engagement of the follower with said spiral thread upon release of said latching means by said tone arm controlled means to enable replaying of the record by manual setting of the tone arm.

13. In an automatic phonograph, a turn-table, a tone arm operably associated with said turn-table, a driving shaft for said turn-table having a spiral thread, a follower having a portion for interfitting with the spiral thread to move said follower longitudinally of the shaft, means connecting said follower to said tone arm for moving the tone arm from a record being played and repositioning it on a record to be played, means for latching the follower against engagement with said spiral thread, and means controlled by the tone arm for releasing said latching means upon backward movement of the tone arm as the stylus of the tone arm traverses an eccentric terminating record groove.

14. In an automatic phonograph, a turn-table, a tone arm operably associated with said turn-table, a driving shaft for said turn-table having a spiral thread, a follower having a portion for interfitting with the spiral thread to move said follower longitudinally of the shaft, means connecting said follower to said tone arm for moving the tone arm from a record being played and repositioning it on a record to be played, means for latching the follower against engagement with said thread, and means controlled by the tone arm for releasing said latching means when the tone arm reaches a predetermined position relative to the center of a record on the turn-table.

15. In an automatic phonograph, a turn-table, a tone arm operably associated with said turn-table, a driving shaft for said turn-table having a spiral thread, a follower having a portion for interfitting with the spiral thread to move said follower longitudinally of the shaft, means connecting said follower to said tone arm for moving the tone arm from a record being played and repositioning it on a record to be played, means for latching the follower against engagement

with said thread, and tone arm controlled means for releasing said latching means, said tone arm controlled means comprising a device operable upon backward movement of the tone arm as the stylus of the tone arm traverses an eccentric terminating record groove for releasing said latching means and a device operated by the tone arm as the stylus of the tone arm traverses the concentric terminating record groove for releasing said latching means.

16. In an automatic phonograph, a turn-table, a tone arm operably associated with said turn-table, means including a cam and a follower for swinging said tone arm, said cam comprising a disc, said follower comprising a resiliently mounted pin, said disc having a generally radial groove receiving the cam and forming a dwell surface, along which the pin moves generally radially of the disc as the stylus of the tone arm traverses a record being played, said disc having a cam groove eccentric to the axis of the disc and along which the pin moves to swing the tone arm, means operable at will for actuating said cam disc, said disc having pin directing surface portions directing the pin into the eccentric groove from the generally radial groove regardless of the position of the pin at the instant actuation of the cam disc is initiated.

17. In an automatic phonograph, a turn-table, a tone arm operably associated with the turn-table, a rotary means for swinging said tone arm, a rotary cam disc, and a cam follower pin connected to said rotary means and yieldably mounted for movement transverse to the face of the cam disc, said cam disc having a pin receiving groove eccentric to the axis of said disc forming an active surface to cause swinging of said tone arm, said disc having a pin receiving cam groove transverse to said eccentric groove at a point of intersection between said grooves, said transverse groove being shaped to permit movement of the pin therein as the stylus of the tone arm traverses a record being played, and said cam disc having entering cam grooves interconnecting opposite ends of said transverse groove to said eccentric groove.

18. In an automatic phonograph, a turn-table, a tone arm operably associated with said turn-table, a shaft for swinging said tone arm, a crank on said shaft, a pin yieldably mounted on said crank, and an actuating cam disc mounted for rotation about an axis spaced from the axis of said shaft and parallel thereto, said cam disc having an actuate groove extending inwardly from the edge of the disc and concentric to the axis of said shaft, said arcuate groove receiving said pin and forming a dwell surface along which the pin moves as the stylus of the tone arm traverses a record being played, said disc having radially spaced grooves eccentric to the axis of said disc for receiving said pin from said arcuate groove, thereby to swing said tone arm and position the same to initiate playing of records of different size, and means including a record sensing member for compelling movement of the pin relative to the cam disc into a selected groove according to the size of the record sensed by said member.

19. In an automatic phonograph, a turn-table, a tone arm operably associated with said turn-table, a shaft for swinging said tone arm, a crank on said shaft, a pin yieldably mounted on said crank, a cam disc rotating on an axis parallel to but spaced from an axis of said spaced shaft, said disc having an arcuate cam groove

concentric to the axis of said shaft and extending generally radially of the disc, said disc being positioned in relation to the pin so that the pin moves along said arcuate cam groove as the stylus of the tone arm traverses a record being played, said disc having spaced grooves eccentric to the axis of rotation of said disc for selectively receiving the pin, said eccentric grooves intersecting said arcuate grooves at points spaced from the axis of the disc so as to position the stylus of the tone arm to initiate playing of a 10-inch record and a 12-inch record, said eccentric grooves being of increasing radius from the axis of the disc in a direction from said points of intersection of said grooves with said arcuate grooves, whereby the pin in traversing either of said grooves swings said tone arm to a position out of the path of a record as it is placed on said turn-table, driving means for actuating said cam disc first in one direction and then the other, means for normally maintaining said driving means ineffective to actuate said cam and constructed to automatically render said driving means ineffective upon completion of each to and fro cycle of rotation of said cam, means controlled by the tone arm for rendering said driving means effective as the playing of each record is completed, said cam disc having a groove intersecting said eccentric grooves, and means including a record sensing member for directing the pin from one eccentric groove to the other along said intersecting groove in accordance with the size of the record sensed by said member.

20. In an automatic phonograph, a turn-table, oscillatable posts adjacent thereto, record supporting and changing blades on said posts and movable therewith, said blades supporting records of different size indiscriminately stacked as to size on said blades, means oscillating said posts to release the bottommost record to said turn-table, a tone arm operably associated with said turn-table, a shaft for swinging said tone arm, a crank on said shaft, a cam disc having a plurality of cam grooves for different size records, a follower pin carried by said crank and selectively engageable with one of said grooves, a record sensing rod oscillatable with and relative to one of said posts, said rod being positioned to sense the bottommost record of the stack of records on said blades, said record sensing rod being mounted relative to the associated post to swing different distances in accordance with the size of the record sensed, and a stop rod connected to said record sensing rod and positioned thereby according to the size of the record sensed, said crank having an arm adapted to engage said stop rod thereby to position the pin follower carried by said crank in a groove of said cam disc according to the position of the stop rod in engaging said crank arm.

21. In an automatic phonograph, a turn-table, means for supporting a stack of records in dispensing relation to said turn-table, said means comprising a shiftable record changing member for successively releasing the records to said turn-table, a tone arm operably associated with said turn-table, a continuously operating driving means for said turn-table, actuator means connectable to said driving means for operation thereby and connected to said record changing member and said tone arm for shifting said record changing member and repositioning said tone arm in an initial playing position for each successive record, releasable latch means for normally holding said actuator means against con-

nection to said driving means, means controlled by the tone arm for releasing said latch means, manually operable control means, means connecting said manually operable means to said latch means for releasing the same at will, and means operated by said manually operable means for rendering said tone arm controlled means ineffective to release said latch means, said actuator means including an automatically releasable connection to said tone arm for permitting manual setting of said tone arm.

22. In an automatic phonograph, a turn-table, means for supporting a stack of records in dispensing relation to the turn-table, said means comprising a shiftable record changing member for successively releasing the records to said turn-table, a tone arm operably associated with said turn-table, a continuously operating driving member, a member urged into driving engagement with said driving member to be driven thereby and connected to said tone arm and said shiftable record changing member for operating the same, means normally latching said driven member out of driving engagement with said driving member, means controlled by the tone arm for automatically releasing said latching means to initiate an operation of said record changing member releasing a record to said turn-table and to initiate simultaneously an operation of said tone arm repositioning said arm for the playing of the next record, an electric motor operating said turn-table and said driving member, a switch for controlling said motor, and manually operable control means including a multi-position manual member, said manually operable control means also including means operable by said manual member in moving to one position to operate said switch to deenergize the motor thereby to cut off the phonograph, means operable by said manual member in moving to a second position to render said latching means ineffective to release said driven member thereby to set the phonograph for manual operation, said last mentioned means being operable by said manual member in moving to a third position to render said latching means effective to release said driven member under the control of said tone arm thereby to set the phonograph for automatic operation, and means operable by said manual member in moving to a fourth position for releasing said latching means thereby to initiate manually at will an operation of said record changing member and said tone arm.

23. In an automatic phonograph, a turn-table, means for supporting a stack of records in dispensing relation to the turn-table, said means comprising a shiftable record changing member for successively releasing the records to said turn-table, a tone arm operably associated with said turn-table, a continuously operating driving member, a member urged into driving engagement with said driving member to be driven thereby and connected to said tone arm and said shiftable record changing member for operating the same, means normally latching said driven member out of driving engagement with said driving member, means controlled by the tone arm for automatically releasing said latching means to initiate an operation of said record changing member releasing a record to said turn-table and to initiate simultaneously an operation of said tone arm repositioning said arm for the playing of the next record, an electric motor operating said turn-table and said driving member, a switch for controlling said motor, and

manually operable control means including a multi-position manual member, said manually operable control means also including means operable by said manual member in moving to one position to operate said switch to deenergize the motor thereby to cut off the phonograph, means operable by said manual member in moving to a second position to render said latching means ineffective to release said driven member thereby to set the phonograph for manual operation, said last mentioned means being operable by said manual member in moving to a third position to render said latching means effective to release said driven member under the control of said tone arm thereby to set the phonograph for automatic operation, means operable by said manual member in moving to a fourth position for releasing said latching means thereby to initiate manually at will an operation of said record changing member and said tone arm, and means presetting said last mentioned means upon movement of the manual member to said second position for automatically releasing said latching means as said manual member is moved from said second to said third position.

24. In an automatic record changer, means for supporting and successively releasing the bottom-most record of a stack, said means including a record supporting member shiftable to release the bottommost record, a tone arm operator constructed to shift the tone arm from one record to the next as the records are changed, a continuously operating driving spiral, a follower adapted to be connected to said driving spiral, and means connecting said record supporting member and said tone arm operator to said follower, said connecting means including a common load release device driven by said follower, and said device being adapted to release automatically and simultaneously the record supporting member and the tone arm operator from the follower upon interference with the operation of said record supporting member.

25. In an automatic phonograph, a stylus carrying tone arm for playing records, means for automatically raising the tone arm from a record when the record has been played and for repositioning said tone arm to initiate playing of a record, said means comprising a driving cam, and a cam follower connected to the tone arm to operate the tone arm, said cam having an active cam portion with a side surface shallow transverse to the direction of traversal of said portion by said follower whereby said follower may move freely relative to said cam across said side surface upon interference with, or manipulation of, said tone arm.

26. In an automatic phonograph, a record receiving turn-table, opposite sets of record supporting and changing blades for receiving a stack of records to be played, said blades being oscillatable to and fro to release records one by one, means for guiding released records to the turn-table, a stylus carrying tone arm mounted for movement toward and from the turn-table and for movement across the turn-table, and means for synchronously operating said changing blades and said tone arm, said means comprising a common driver, and a common load release device connecting said driver to said blades and to said tone arm, said device comprising a driving member and a driven member relatively movable into and out of engagement, means normally urging said driven member into engagement with said driving member, said driving and driven members

having complementary cam-shaped projections and recesses adapted for automatically moving said members out of engagement upon interference with the operation of said changing blades.

27. In an automatic phonograph, a stylus carrying tone arm for playing records, means for automatically moving the tone arm from one record to the next, said means including a driving cam having level edged grooves, and a conical ended cam follower connected to the tone arm to operate the tone arm and yieldably pressed into releasable engagement with the cam grooves whereby said follower may move freely out of said cam grooves upon interference with, or manipulation of, said tone arm.

28. In an automatic phonograph, a pivotally mounted tone arm adapted to carry a record playing stylus, and means for automatically shifting the tone arm from one record to the next, said means including a crank connected to said tone arm, a cam follower pin slidably mounted in said crank and a driving cam having grooves engaging said follower pin, said follower pin being releasably urged against said cam grooves, said cam grooves and cam follower pin having bevelled engaging surfaces to automatically release said follower pin out of said cam grooves upon interference with, or manipulation of, said crank by said tone arm.

29. In an automatic phonograph, a record receiving turn-table, means for feeding records successively to said turn-table, said means including a shiftable record changing member, a driver therefor, and means including releasable clutch members normally resiliently engaged in driving relation for connecting said record changing member to said driver, said clutch members having complementary engaging countersunk sur-

faces resiliently held in engagement, the edges of said countersunk surfaces being bevelled to automatically allow said members to move out of engagement upon interference with the movement of said record changing member.

30. In an automatic phonograph, a record receiving turn-table, a tone arm adapted to carry a stylus for playing records on said turn-table, means for shifting said tone arm from one record to the next, said means including a driver, and means including releasable clutch members normally resiliently engaged in driving relation for connecting said driver to said tone arm, said clutch members having interengaged countersunk surfaces with bevelled edges, whereby they will release automatically upon subjection of said latch to an overload.

JAMES L. DONALDSON MORRISON.
